UNITED STATES PATENT OFFICE

AUDREY L. HAMPTON, OF HOUSTON, TEXAS

OVERSHOT

Application filed February 26, 1932. Serial No. 595,270.

This invention relates to an overshot.

An object of the invention is to provide a tool of the character described adapted to pass over the upper end of a pipe stuck in a well bore and to engage the outer surface of said pipe whereby the stuck pipe may be removed.

Another object of the invention is to provide an overshot of the character described embodying novel means whereby the overshot may be released from the pipe for removal from the well in case the stuck pipe can not be pulled.

With the above and other objects in view the invention has particular relation to certain novel features of construction, operation, and arrangement of parts, an example of which is given in this specification and illustrated in the accompanying drawing, wherein:—

Figure 1 shows a vertical sectional view of the tool.

Figure 2 shows a side elevation thereof partly in section, and

Figure 3 shows a cross sectional view taken on the line 3—3 of Figure 1.

In the drawings the numeral 1 designates a tubular body having the downwardly converging seat 2 therein and whose upper end is provided with the internal coarse threads 3.

Within the body beneath said seat there is a flexible packer or cup ring 4 which tapers upwardly and which is seated against the inside shoulder 5 of the body and retained therein by the annular retainer ring 6. Screwed into the lower end of the body and abutting the ring 6 there is a guide shoe 7 whose lower end is flared as at 8 whereby the body may be guided over the upper end of the stuck pipe 9 as the tool is lowered.

The tool may be attached to the tubular operating string 10 by means of a suitable coupling 11.

Within the body there is a tubular operating nipple 12 whose upper end has a head 13 provided with the external coarse threads 14 which are in mesh with the threads 3. This nipple is accordingly spaced inwardly from the body 1 and the nipple is provided with one or more vertical slots 15.

Within the body 1 above the seat 2 there is a slip 16 of a general tubular form. The lower end of the slip is provided with the vertical slots 17 extending from the lower end thereof thus providing the flexible arms 18 and the lower ends of these arms are provided with the wedge shaped jaws 19 whose inner sides are toothed and whose outer sides are tapered to conform to the pitch of the seat 2. The upper end of the slip has the vertical slots 20 extending to the upper end thereof and preferably arranged staggered with the relation to the slots 17 and thus providing the flexible arms 21. The upper ends of these arms 21 have the inwardly extending studs 22 which project through the slots 15. In assembly the arms 21 may be sprung over the lower end of the nipple 12 and the studs 22 brought into registration with the slots 15 whereupon said studs will be projected through said slots.

In use the tool may be assembled as shown in Figure 1 and let down into the bore and the guide shoe 7 will guide the tool over the upper end of the stuck pipe.

The lower end of the shoe 7 may be formed into a wall hook as 23 shown in Figure 2 so that in case the upper end of the stuck pipe is lying against the wall of the well, the tool may be rotated to engage the hook 23 with the upper end of said pipe to center said upper end in the bore so that the shoe may guide the tool over the upper end of the pipe. In assembling the tool preparatory to lowering the same into the bore the nipple 12 should be screwed downwardly on the threads 3 so that the jaws 19 may seat on the seat 2. As the tool is lowered the jaws 19 will frictionally engage the stuck pipe so as to hold the jaws slightly above the seat 2, the slots 15 being elongated sufficiently to permit this.

When the tool has been lowered over the upper end of the stuck pipe an upward pull may then be exerted through the string 10 and the seat 2 will engage the outer surface of the jaws 19 and will cause said jaws to securely grip the pipe to be pulled and a further upward pull may result in the dislodgment of the stuck pipe whereupon it may be removed from the bore. To assist in

dislodging the pipe water may be forced under pressure down through the string 10 and this water will be forced, by the packer, or cup ring, 4 to enter and pass down through 5 the stuck pipe and return up around the outside of said stuck pipe, whereby said pipe may be washed loose and may then be readily removed.

If the pipe 9 is stuck in the bore so tightly 10 that it can not be dislodged, it will be necessary to release the tool from the pipe to remove the tool. In order to release the tool, the operating string and body 1 may be rotated to the right and during this rotation the 15 friction of the jaws 19 with the pipe will hold the nipple 12 stationary, that is, will prevent said nipple from turning and the body will move downwardly relative to said nipple and relative to the jaws 19 thus unseating the seat 2 from said jaws and permitting the jaws to expand sufficiently to release the pipe whereupon the tool may be readily withdrawn from the well bore.

The drawing and description disclose what 25 is now considered to be a preferred form of the invention by way of illustration only while the broad principle of the invention will be defined by the appended claims.

What I claim is:

30 1. An overshot for engaging and pulling a pipe in a well, comprising a tubular body having a downwardly converging inside seat, a tubular slip in said body shaped to surround the pipe and having engaging jaws 35 whose outer surfaces taper downwardly and whose inner surfaces have pipe engaging teeth, a tubular nipple having a threaded connection with said body, said slip and nipple being provided, one with a longitudinal 40 bearing and the other with a flexible arm having a projection which works in said bearing.

2. An overshot for engaging and pulling a pipe stuck in a well bore and comprising a 45 tubular body, having a downwardly converging seat, a tubular slip in said body adapted to pass over the pipe to be pulled and having expandible pipe gripping jaws carried thereby shaped to seat in, and to be contracted by, said seat, flexible arms upstanding from the slip, a tubular slip actuator having a threaded connection with said body and an adjustable connection with said arms, and a yieldable packer in the body beneath said seat adapted to closely surround said pipe.

50 3. An overshot for engaging over, and pulling, a pipe in a well bore, and comprising a tubular body, a slip actuator in, and having a threaded connection with, said body, 55 a tubular slip having downwardly tapering, contractile, pipe engaging means adapted to surround said pipe, a downwardly tapering seat in the body beneath said engaging means, flexible arms carried by said slip, operative 60 connections between the arms and slip actu-

ator whereby said slip may be moved longitudinally in the body upon the rotation of the body relative to the slip.

4. An overshot fishing tool comprising a 70 tubular body having a downwardly converging seat therein and whose upper end is provided with internal threads, a tubular operating nipple within the body having an externally threaded enlarged head thereon in mesh with the threads of said body, a slip 75 within the body having depending flexible arms and wedge shaped jaws at the lower ends of said arms arranged to be contracted by said seat, flexible upstanding arms carried by said slip and arranged around the lower end of said nipple, said nipple and upstanding arms being provided one with vertical slots and the other with studs which work in 80 said slots.

In testimony whereof I have signed my 85 name to this specification.

AUDREY L. HAMPTON.
